No 999

Dec. 999

R. Wheeler, and S. A. Bailey, of Utica, N.Y.

Letters Patent No. 999, dated, May 4, 1858

The schedule referred to in these Letters Patent & making part of the same.

To all whom it may concern:—

Be it Known that we Russell Wheeler and Stephen Bailey, of the city of Utica, in the County of Oneida, and State of New York have invented, or produced a new and original design for the external configuration of Kitchen cooking stove, and we do hereby declare that the following, is a full and exact description of the same, reference being had to the annexed drawing, and to the letters of reference marked thereon,

The stove stands upon three legs ornamented in front a, b, c. The hearth d, is plain, without ornament, except a border of consecutive elevations as seen upon the margin in the drawing. The fireplace e, ended in the ordinary manner, back of the hearth, is ornamented in front by four panels; the two middle ones are alike in their configuration, and form in the usual manner a double door for the fireplace in front. The front of each door is surrounded by a quadrangular border of bead-like elevations of a somewhat conical shape. Within this border is another quadrangular figure, with scalloped internal edges, presenting their concave lines inward; and this surrounds a central figure, having its external edge scalloped also, but presenting their concave lines outward, with several raised lines within, corresponding to the exterior of the figure, and a star in the middle. On either side of these is a narrow oblong panel, with a similar external border: the interior space being occupied by a single, oblong, scalloped figure presenting its convex outward, as shown in the drawing. The end plates, or doors are ornamented similarly, in one quadrangular panel each resembling substantially those first described in front.

The top f, of the fireplace, and flue, extending back to the base of the oven, is not ornamented except a double row of consecutive elevations from an inclined margin all round the plate.

The four plates which constitute the elevation of the oven h, are ornamented; The front and rear plate according to one pattern, and the two end plates of another. The side plates, front and rear, have two panels each, of an oblong quadrangular shape, both included within one common border k, having a partition m, in the middle which separates the two panels. Each panel is again surrounded by the aforesaid bead-like border, and then a lighter serrated line, and the included space is occupied by an

oblong starlike figure P, with a concave, scalloped margin. The end panels S, have the same central ornament, and the bordering possesses the same characteristics substantially; but instead of being rectangular at the top, the lines of the bordering are arched. The sloping sides of the top plate, m, are ornamented by parallel lines, of small bas-relief figures, the external or lower one being of a somewhat heavier description, and extending quite round upon the margin of the plate. The ornamental figures are generally in bas-relief, and the various parts are substantially shown in the annexed drawing.

What we claim as new and desire to secure by Letters Patent, is the external configuration of the above described stove.

End Witnesses:—

John J. C. Bailey.
